INVENTOR.

BY *David S. Jacobus*
Gifford & Bell
ATTORNEYS

UNITED STATES PATENT OFFICE.

DAVID S. JACOBUS, OF JERSEY CITY, NEW JERSEY, ASSIGNOR TO THE BABCOCK & WILCOX COMPANY, OF BAYONNE, NEW JERSEY, A CORPORATION OF NEW JERSEY.

REGULATING DEVICE.

Original application filed December 14, 1916, Serial No. 136,832. Divided and this application filed September 4, 1918. Serial No. 252,551.

To all whom it may concern:

Be it known that I, DAVID S. JACOBUS, a citizen of the United States, residing in Jersey City, in the county of Hudson and State 5 of New Jersey, have invented certain new and useful Improvements in Regulating Devices, disclosed in the following specification.

My invention is disclosed in my prior Patent No. 1,328,997 granted January 27, 1920, 10 and of which the present application is a division.

My invention relates to a regulating device in which an actuating member, which is preferably operated by fluid pressure, is 15 controlled by a fluid pressure operated controlling device. I have illustrated my invention in connection with a system that regulates the temperature of superheated steam, the regulator mechanism being responsive to 20 the temperature of the steam. It is to be understood, however, that my invention is equally applicable to any system in which there is a variable pressure, and in which it is desired to actuate a regulating device in 25 response to such pressure variations. One application of my present invention is illustrated in my prior Patent No. 1,328,997 where the power-actuated member is shown connected to doors in a superheater setting, 30 by which the amount of superheat is controlled or regulated.

In the drawings which illustrate one embodiment of my invention, Fig. 1 is a diagrammatic view illustrating the principle of 35 operation of my invention, and Fig. 2 is a side view, mainly in section, showing details of the valve and parts associated therewith for controlling the admission of fluid to a power-operated cylinder.

40 In the adaptation, hereinafter described, of my invention to superheater practice, I employ a thermostat placed in the path of the outgoing superheated steam. In the form shown, this comprises a container for a 45 volatile liquid, the temperature of such liquid, and consequently the pressure of its vapor, varying as the temperature of the surrounding superheated steam varies. This vapor pressure generated in the container is 50 utilized to set in operation certain mechanisms to limit the temperature within the superheater setting and thus limit the degree of superheat. For the purpose of ex-

plaining the principle of operation of my invention, I have shown a diagrammatic arrangement in Fig. 1 in which the numeral 1 designates a portion of the superheated steam main. Within this main is a container in the form of a coiled pipe 2 closed to the steam and containing a volatile liquid such as water, alcohol or mercury having a fixed 55 boiling point for a given pressure. The container may have any appropriate form which will insure an effective impingement of the superheated steam and a relatively large 60 heating surface with the proper internal volume. The upper end of the coil 2 is secured in an opening in the cap 3 closing the end of the steam main, said cap having a chamber 4 from which a pipe 5 leads to a 65 regulator. The coil 2 is only partially filled with liquid, the space above the liquid being filled with vapor, the pressure of which corresponds to the temperature to which the liquid is heated by the superheated steam. 70 The controlling mechanism comprises a chamber 6 having a flexible diaphragm 7 upon which diaphragm rests a disc 8. When water is used as the liquid in the coiled pipe 2 the chamber 6 is filled with water upon the 75 surface of which oil is placed to prevent corrosion of the diaphragm 7, which is preferably of hardened steel. For a given steam 80 temperature passing over the coil 2 there will be a given vapor pressure transmitted to the 85 chamber 6. This pressure acting upon the under side of the diaphragm 7 is transmitted through the following mechanism:

The post which bears on the disc 8 is pivoted to a lever 9 having its fulcrum at 10. 90 The lever is normally depressed by a spring 11 connecting the same to the frame. The tension of the spring 11 may be adjusted by a nut 10^a which is received on the end of the spring member and engages a part of the 95 frame. This affords a ready means of adjusting the controlling mechanism to operate at any desired pressure. The upward movement of the lever 9 is preferably limited by means of a stop 12. The free end of the lever 10 is connected by a stem 13 to a valve 14, which valve controls the admission of fluid from an inlet pipe 15 to a passageway 16 and a chamber 17 within the valve casing, which chamber 105 communicates with the motor cylinder 18. The motor piston 19 is connected by a piston

rod 20 to a power actuated member or lever 21 for operating a regulator, the same being fulcrumed at 22 on a link 23. The lever 21 is preferably counterweighted at 24 and is connected to a rod 25 the movements of which are utilized to control the temperature of the superheated steam, as more fully disclosed in my prior application, which control may be effected by admitting air around the superheater. The power actuated member or lever 21, which is actuated by the piston 19, is thus governed by a controlling mechanism actuated by fluid pressure.

The action of the controlling mechanism above described is to cause the vapor pressure generated in coil 2 to act through the mechanism in such a manner that when the temperature of the superheated steam flowing through the main 1 exceeds that for which the apparatus is set, the lever will be raised to open the valve 14 and thereby admit water under pressure to the working side of the piston 19. When the piston 19 is moved the power lever 21 will be correspondingly moved and thereby the rod 25, the movement of which effects a reduction in the temperature of the superheated steam, as fully disclosed in my prior application.

In the arrangement shown in my prior application, when the temperature of the steam is reduced below that at which the apparatus is set, the valve corresponding to the valve 14 was moved to its seat by the spring 11. In the practical application of the apparatus shown in Figures 1 to 8 of the device shown in that application, however, it was found that the doors for admitting air into the setting would not at all times close until after the temperature of the superheated steam had fallen a considerable amount below that at which the doors were opened. This was due to the use of an unbalanced valve and friction losses. For example, if the doors opened when the superheated steam reached a temperature of 500° F. they would sometimes fail to close before the temperature had fallen to 475° F. Under most conditions of operation as an emergency device this falling of the temperature of the superheated steam below that at which the doors are opened is not objectionable, as the fireman or attendant can readily press down the lever 9 after the superheated steam has been reduced to the desired degree and thus bring the apparatus to its initial condition in which it will remain until the temperature of the steam flowing over the coil 2 again reaches the temperature to which the apparatus is set.

In accordance with my present invention provision is made for closing the doors which admit air to the setting immediately after the temperature of the steam flowing over the coil 2 falls below that at which the

apparatus is set. In this construction the valve spindle 13 is connected to the end of the lever 9, the valve 14 normally closing the end of the water inlet 15. When the valve is opened water flows through passage 16 raising ball-valve 26, thence into the chamber 17, from which the water is admitted into the power cylinder 18. During the time that the valve 14 is open and the piston 19 is descending, a portion of the water from chamber 17 flows through the outlet 27 into waste pipe 28 in a manner similar to that disclosed in my prior application, the duct opening being controlled by valve 27'. The valve casing is formed with a vertical channel 29 which communicates with the chamber 30 in which the valve moves, through a duct 31 leading from the lower part of the chamber and controlled by a valve 32. That portion of channel 29 which is below duct 31 is connected by a pipe 33 with a power cylinder 18, said pipe entering the cylinder at a point which causes it to be closed by the piston on its downward movement. The lower end of the cylinder is closed by a head 34, and a drain-pipe 35 connects the cylinder with the waste-pipe 28. The upper end of channel 29 above duct 31 is connected by a duct 36 with the chamber 37 in the valve casing above an auxiliary piston 38 which is secured to valve-stem 13.

When the temperature of the superheated steam flowing over coil 2 reaches that at which the apparatus is set to operate, lever 9 will be raised, thereby opening valve 14 to admit water under pressure to the power piston, as before described. When water is admitted to chamber 30 a portion of it flows through duct 31 to the two branches of channel 29. That portion flowing through the lower branch is conducted by pipe 33 to the lower part of cylinder 18 so that during the descent of the cylinder, so long as the outlet of pipe 33 remains open, the water so admitted will escape through the drain connection 35 to waste-pipe 28. The water which flows through the upper part of channel 29 is conducted through duct 36 to the chamber 37 above piston 38. There is, however, a comparatively low pressure in the upper part of channel 29 during the time that water flows freely through pipe 33. When piston 19 reaches the end of its downward stroke it covers the opening from pipe 33, thereby stopping the flow of water through said pipe and causing the water to flow through the upper part of channel 29 to chamber 37, the upward movement of piston 38 not having been sufficient to close completely duct 36. When the pressure in chamber 37 becomes great enough to overcome the resistance of valve 14 and the parts associated therewith, and provided the temperature of the superheated steam flowing over coil 2 is such that

there is not too great an unbalanced force tending to maintain the lever 9 in its upper position, the pressure acting on the upper side of piston 38 will close the valve 14. 5 When the valve is so closed, ball-valve 26 will close and piston 19 will move upward so as to open the end of pipe 33 and all the parts that effect the opening of the valve 14 will be restored to normal position, that is, 10 the valve 14 will be automatically closed as soon as the piston 19 reaches the limit of its downward stroke and the piston will return to its original position at the top of the power cylinder if the temperature of 15 the superheated steam flowing over the coil 2 does not exceed the limit for which the apparatus is set, thus closing the doors in the setting through the system of levers connected to piston 19, as more fully disclosed 20 in my prior application. Valve 14 will then remain closed until the temperature of the superheated steam flowing over coil 2 exceeds the limit for which the apparatus is set. If, therefore, the opening of doors for 25 admitting air into the setting, or the manipulation of dampers, as more fully described in my prior application, causes the temperature of the steam flowing over coil 2 to be reduced to the required degree, valve 30 14 will remain closed and the power piston will return to its normal position, thus closing the air admission doors.

If the temperature of the superheated steam flowing over the coil 2 still exceeds 35 the limit for which the apparatus is set when the piston 19 reaches the limit of its downward stroke, the piston 19 will start to return to its original position, but immediately the opening into the cylinder at the 40 discharge end of the pipe 33 is opened and the pressure is sufficiently lowered in the pipe 33, the valve 14 will be opened by the lever 9 and the power piston 19 will be forced downward. Forcing the power piston 45 ton downward will again close the opening into the cylinder at the discharge end of pipe 33, which will again cause the piston to rise. As long, therefore, as the temperature of the superheated steam flowing over the 50 coil 2 is in excess of the limit for which the apparatus is set, the power piston 19 will remain near the limit of its downward stroke, moving slightly up and down in the way described, thereby setting and resetting 55 the apparatus by bringing the valve 14 to its initial position. As long as the temperature of the superheated steam flowing over the coil 2 remains above the limit for which the apparatus is set, the power piston 19 60 will remain near the limit of its downward stroke, and by remaining near the limit of its downward stroke it will serve to keep the doors which admit air to the setting open for the purpose of reducing the temperature 65 of the superheated steam to the desired

point. As soon as the temperature of the superheated steam is reduced to below the limit for which the apparatus is set, the valve 14 will remain closed, and the power piston will then travel upward to its initial 70 position.

The arrangement described regulates the temperature very closely by overcoming the friction losses referred to above. It will be obvious that when the temperature rises to 75 the predetermined point, the pressure in the chamber 6 will be obliged to overcome not only the resistance of the spring 11 but also the resistance due to the friction of the various parts between the diaphragm and the 80 valve 14. Or, to express it somewhat differently, the spring 11 is adjusted so as to produce a pressure which when added to such frictional resistances will permit the valve 14 to open when the predetermined 85 temperature, and therefore the predetermined pressure in chamber 6, has been reached.

When the temperature drops below the predetermined point, however, the tendency 90 of the spring 11 to close valve 14 will be resisted to some extent by the friction of the parts, so that the pressure in the chamber 6 must fall considerably below that required to open valve 14 before valve 14 can close. The friction of the parts, being a constant 95 resistance to the motion of the lever 9 in both directions, is added to the pressure of the spring 11 to resist opening, and is subtracted from the pressure of the spring 11 to resist closing.

By providing the additional counterpressure derived from the piston 38, I am enabled to neutralize the frictional resistance 100 so that the pressure tending to close the valve will be the same as the resistance against its opening, since this counterpressure is applied only after the controlling mechanism operated by the pressure in chamber 6 has operated. 110

For example, if it should be assumed that the total pressure in chamber 6 must be five hundred pounds in order to open valve 14 and that the resistance to this pressure is made up of ten pounds due to the friction 115 of the parts, and four hundred and ninety pounds due to the spring 11, then when the temperature falls below the degree which gave a pressure of five hundred pounds in chamber 6, this pressure would have to fall to four hundred and eighty pounds before valve 14 would close, unless my novel mechanism is used. By arranging the pressure on piston 38 so that it will be equivalent to twenty pounds on the chamber 6, or to more 120 than twenty pounds, then the effect of the frictional losses will be nullified, or more than nullified, because the pressure tending to close the valve will be the total of the spring 11, of four hundred and eighty 130

4
pounds, and of the piston 38 of twenty pounds, or five hundred pounds in all, the same pressure at which the valve was opened.

5 Primarily, therefore, my present device is an arrangement by which the counterpressure tending to close the valve 14 will be made sufficient to close the valve 14 when the power piston 19 approaches the limit of 10 its travel, thereby resetting the apparatus so that slight variations of temperature, or any other conditions to be regulated, will cause the power-actuated member either to oscillate back and forth through a small distance near the limit of its travel if the temperature or other conditions for which the apparatus is set are exceeded, or will cause the power-actuated member to return to its initial position if the temperature or the 20 other conditions are not exceeded.

Any leakage from chamber 37 around spindle 18 passes into a chamber 39 below piston 38 and thence through passage 40 to a waste pipe 41. A partition 42 separates 25 chamber 37 from the chamber or water space 30 in which the valve 14 moves. Any leakage through the spindle opening in partition 42 will flow into chamber 39 and thus to waste-pipe 41. A strainer 43 in the inlet 30 pipe 15 prevents the entrance of any solid material into the cylinder 18.

The form of my invention illustrated in the present drawings may be employed in a superheat regulating device as well as in a 35 superheat limiting device. When used in connection with a superheat regulating device the amount of superheat would ordinarily be governed by means other than allowing cold air to flow into the furnace or setting, 40 the means employed being preferably of such a nature as not to lower the efficiency of the apparatus.

In a superheat regulating device, as well as in some other regulating devices, it is 45 highly important that the regulator respond to bring the parts to the proper position immediately the desired temperature is secured, either with a rising temperature or a falling temperature. The form of apparatus covered by my invention is particularly adapted to this class of service as it 50 is reset each time that it reaches the limit of its travel and will therefore act as promptly to respond to a temperature when the fluid in which the temperature is being regulated 55 is increasing as it will when it is decreasing, or vice versa.

While I have illustrated my device as applied to a temperature-regulating arrangement in which the power-actuated member is operated by fluid pressure, it will be understood that such arrangement may be widely varied. Any suitable thermostat 60 may be used to control the application of power to the power-actuated arm, and any

form of power mechanism or motor other than the hydraulic motor which I have illustrated, may be used.

What I claim and desire to secure by Letters Patent of the United States is:—

1. In a device of the class described, a member, means to move the member towards normal position, a motor connected to the member to move it out of normal position when the motor is operated, a thermostat 75 to control the application of power to the motor, and mechanism, independent of the thermostat, to shut off the application of power to the motor when the member has been moved out of normal position, the motor being arranged to permit said mechanism to move the member towards normal position when the power to the motor is shut off.

2. In a device of the class described, a member, means to move the member towards normal position, a motor connected to the member to move it out of normal position when the motor is operated, a fluid-pressure actuated device to control the application of power to the motor, and mechanism, independent of the fluid-pressure-actuated device to shut off the application of power to the motor when the member has been moved out of normal position, the motor being arranged 80 to permit said means to move the member towards normal position when the power to the motor is shut off.

3. In a device of the class described, a member, means to move the member towards normal position, a fluid-actuated motor, comprising a motor cylinder and a motor piston therein, connected to the member and arranged to move the member out of normal position when fluid pressure is applied to the motor piston, a valve to control the application of fluid pressure to the motor piston, a fluid-pressure-actuated device connected to the valve to open the valve when the pressure on said device reaches a predetermined amount, and means, independent of the fluid-pressure-actuated device to relieve the fluid pressure against said motor piston, to permit the member to be moved toward normal position.

4. In a device of the class described, a member, means to move the member towards normal position, a fluid-actuated motor comprising a motor cylinder and a motor piston therein, connected to the member and arranged to move the member out of normal position when fluid pressure is applied to the motor piston, a valve to control the application of fluid pressure to the motor piston, a fluid-pressure-actuated device connected to the valve to open the valve when the pressure on said device reaches a predetermined amount, means, independent of the fluid-pressure-actuated device, to close said valve and means to permit the fluid in said 130

motor cylinder to escape when said valve is closed, to permit the member to return toward normal position.

5. In a device of the class described, a member, means to move the member towards normal position, a fluid-actuated motor comprising a motor cylinder and a motor piston therein, connected to the member and arranged to move the member out of normal position when fluid pressure is applied to the motor piston, a valve to control the application of fluid pressure to the motor piston, a fluid-pressure-actuated device connected to the valve to open the valve when the pressure on said device reaches a predetermined amount, an auxiliary piston connected to said valve, means, independent of the fluid-pressure-actuated device, to apply pressure to said auxiliary piston to close said valve when the motor piston has been moved, and means to permit the fluid in the motor cylinder to escape when said valve is closed, to permit the member to return toward normal position.
- 25 6. In a device of the class described, a member, means to move the member towards normal position, a fluid-actuated motor comprising a motor cylinder and a motor piston therein, connected to the member and arranged to move the member out of normal position when fluid pressure is applied to the motor piston, a valve to control the application of fluid pressure to the motor piston, a fluid-pressure-actuated device connected to the valve to open the valve when the pressure on said device reaches a predetermined amount, an auxiliary piston connected to said valve, means, operated by the motor piston, to apply pressure to said auxiliary piston to close said valve when the motor piston has been moved by the opening of said valve, and means to permit the fluid in the motor cylinder to escape when said valve is closed, to permit the member to return toward normal position.
- 45 7. In a device of the class described, a member, means to move the member towards normal position, a fluid actuated motor, comprising a motor cylinder and a motor piston therein, connected to the member and arranged to move the member out of normal position when fluid pressure is applied to the motor piston, a valve to control the application of fluid pressure to the motor piston, a fluid-pressure-actuated device connected to the valve to open the valve when the pressure on said device reaches a predetermined amount, means, independent of the fluid-pressure-actuated device, to close said valve, and a permanently-open outlet in said motor cylinder to permit the fluid therein to escape, to permit the member to return toward normal position.
- 65 8. In a device of the class described, a valve, a pressure-actuated device, connec-
- tions between the valve and said device arranged to open the valve when the pressure on said device has reached a predetermined amount, means to hold the valve on its seat, and valve closing means independent of the means to hold the valve on its seat and operative only when the valve is open, to exert a closing pressure on said valve substantially equal to the frictional resistance of the connections between the valve and the pressure-actuated device.
9. In a device of the class described, a member, means to move the member toward normal position, a motor connected to the member to move it out of normal position when the motor is operated, and means to control the application of power to the motor, including a lever, constantly acting means to hold the lever in normal position to shut off the power to the motor, a fluid-pressure actuated device arranged to exert a pressure against the lever to move it away from normal position, and a supplemental power device to move the lever toward normal position and operative only after the lever has been moved away from normal position by the fluid-pressure device against the pressure of the constantly acting means.
10. In a device of the class described, a motor and means to control the application of power to the motor, including a temperature-controlled fluid-pressure actuated device, a lever connected to said device to be moved by the expansion of the fluid in said device, constantly acting means to hold the lever in normal position and a supplemental power device arranged to exert pressure on said lever to return it to normal position only after the lever has been moved out of normal position by the fluid-pressure device against the pressure of the constantly acting means.
11. In a device of the class described, a fluid operated motor and a valve to control the application of power to the motor, a lever connected to the valve, a spring to hold the lever in normal position with the valve closed, a fluid-pressure device subjected to varying temperatures, a plunger arranged to be moved by the fluid in said device when the temperature rises, said plunger being connected to the lever to move it from normal position to open the valve against the pressure of the spring, supplemental power means to exert pressure on the lever to move it toward normal position to close the valve, and means to cause said supplemental power means to be thrown into operation only after the lever has been moved out of normal position to open the valve to actuate the motor.
12. In a device of the class described, a member, means to move the member toward normal position, a motor connected to the member to move it out of normal position,

and means to control the application of power to the motor, including a lever, a fluid-pressure actuated device to move the lever out of normal position, means to move the lever toward normal position and supplemental power means to move the lever toward normal position with a force substantially equal to the frictional resistance of the parts, and means to render said supplemental power operative only after the motor has moved the member out of normal position, said motor being arranged to permit the member to move back to normal position

when the power is shut off by the lever, whereby the member may be moved out of normal position and returned thereto immediately after the pressure in said fluid-pressure device rises above or falls below a predetermined amount.

In testimony whereof I have hereunto signed my name in the presence of two subscribing witnesses.
